UNITED STATES PATENT OFFICE.

WILLIAM MOSSO, OF NEFFS, OHIO.

MINER'S LAMP.

1,324,921.

Specification of Letters Patent. Patented Dec. 16, 1919.

Application filed December 2, 1918. Serial No. 264,895.

To all whom it may concern:

Be it known that I, WILLIAM MOSSO, a citizen of the United States of America, and resident of Neffs, county of Belmont, and 5 State of Ohio, have invented certain new and useful Improvements in Miners' Lamps, of which the following is a specification.

This invention relates broadly to acetylene gas lamps, and more specifically to a 10 gas lamp of that type commonly employed by miners.

The primary object of the invention is to provide an acetylene gas lamp embodying two separate carbide containers or gas 15 generating tanks designed for independent and consequently alternate use, and including means whereby the removal of either of said containers for recharging may be accomplished while gas from the other con-

20 tainer is utilized for furnishing light.

A further object is to provide a miners' gas lamp which is simple in construction, which has its parts compactly arranged and readily accessible for cleaning, which is 25 light in weight, and which is particularly efficient in operation.

A further object is to provide a lamp of the character mentioned having a single adjustable valve whereby the flow of the water 30 to and the passage of gas from both carbide containers is controlled.

With these and other objects in view, the invention resides in the features of construction, arrangement of parts and combinations 35 of elements which will hereinafter be fully described, reference being had to the accompanying drawings, in which—

Figure 1 is a view of the invention partly in rear elevation and partly in vertical section;

Fig. 2 is a side elevation of the same;

Fig. 3 is a horizontal section on line 3—3, Fig. 1;

Fig. 4 is a front elevation of the reflector;

Fig. 5 is an enlarged section on line 5—5, Fig. 3; and—

Figs. 6 and 7 are sections taken on lines 6—6 and 7—7, respectively of Fig. 5.

Referring to said drawings, in which like 50 designating characters distinguish like parts throughout the several views—

1 indicates a water reservoir having a 55 filler opening in the top thereof provided with a removable cap or cover 2 which is preferably hinged to said reservoir as shown

at 3 in Figs. 1 and 2. Rigidly carried by the bottom 1^a of the reservoir are two depending cylindrical supports 4. Each of said supports has its lower end screw threaded for receiving thereon the upper 60 threaded end of a cylindrical cup or carbide container 5. Each of said cups 5 has an annular terminal flange 6 adapted to seat against a corresponding collar-like flange 7 carried by its support 4 above the 65 screw threads of the latter and at a suitably spaced distance from the bottom of the water reservoir 1.

Said cups or containers 5 and their supports 4 together constitute gas generating 70 tanks. Either of said containers may be readily detached, as for replenishment with carbide, while the other functions to furnish gas.

Soldered or otherwise suitably attached 75 to the under side of the bottom 1^a of the reservoir 1 between the two containers 5 and occupying a position above the flanges 7 of the latter is a valve body 8 having a forwardly extending horizontal portion 8^a 80 of suitable length. Extending longitudinally into said valve body 8 through its portion 8^a is a socket 9, preferably of slightly tapered form, in which is seated a correspondingly shaped rotatable valve 10 which 85 has its outer end reduced, forming an annular shoulder 11. A cap nut 12 is threaded upon the outer end of the portion 8^a of the valve body into seated relation to the shoulder 11 and is adapted for adjustment 90 to maintain said valve plug 10 against chance rotation.

Suitably attached to the opposite sides of the valve body 8 and communicating with the socket 9 through opposite horizontal 95 ports 13 are the horizontal upper ends of two substantially L-shaped tubes 14 designed to conduct water to the interiors of the gas generating tanks, said tubes having said ends extended through the supports 4 and 100 having their lower ends located centrally of said containers 5 at a suitable height above the bottoms of the latter. A vertically disposed port 15 leads through the bottom 1^a of the reservoir and the valve body and 105 serves as a passage for conducting water from the reservoir to the socket 9. The valve plug 10 has an arcuate peripheral recess 16 located therein in such position that it coincides with, and provides an avenue of 110

communication between, the port 15 and one or the other of the ports 13 according as the said valve plug is rotated forward or back.

Also attached to the opposite sides of the 5 valve body forward of the positions occupied by the water-conducting tubes 14 are the ends of two oppositely extending alined horizontal gas conducting tubes 17. Said tubes are extended through the supports 4 10 and are designed to conduct gas generated within the tanks to ports 18 leading through the valve body 8 to opposite sides of the socket 9.

The valve plug has a small central bore 19 15 extending longitudinally therethrough from its front end to a point which, in the seated position of said plug, is adjacent to the ports 18; and leading outward from the inner end of said bore or passage 19 to an arcuate peripheral recess 20 provided in said plug is a port 21.

The reduced outer end 10^a of the valve plug which, as hereinbefore indicated, also 25 performs the function of a gas conducting tube, may have fitted thereon a separate burner tip of the usual form, or it may itself serve as a burner tip, as shown in Fig. 5.

In practice, when the valve plug is turned 30 to the position shown in Fig. 6, water from the reservoir 1 is supplied to the left hand gas generating tank through the vertical port 15, the left hand horizontal port 13 and the communicating tube 14, the recess 16 in 35 the valve plug 10 being then in a position permitting communication therethrough between said ports 15 and 13. In said position of the valve, gas is permitted to feed from said left hand tank to the burner tip, the 40 recess 20 in the plug 10 being then disposed with a portion thereof in register with the left hand gas port 18, as shown in Fig. 7, and the gas being consequently permitted to pass through the gas tube 17 of said left 45 hand tank, the said port 18, recess 20, port 21 and the passage 19.

To cut off the supply of gas from the left hand tank and to simultaneously provide for furnishing gas from the right hand tank 50 to the burner, the valve plug is given a partial turn to the right, thereby carrying the recesses 16 and 20 out of register with the left hand ports 13 and 18, respectively, and into register with the right hand ports 13 55 and 18.

Relief ports 22 of relatively small capacity are provided in the valve plug 10 at points where one or the other thereof, according as gas is being permitted to feed 60 from the right or left hand tank, will register with the port 18 opposite that through which the gas is then feeding, as shown in Fig. 7, the purpose being to permit of the passage through such relief port of any gas 65 which may be generated in the adjacent tank

following the shifting of the valve to a reverse position.

A reflector 23 is suitably mounted behind the burner tip, the same being preferably rigidly mounted, as by soldering, upon the 70 adjustable cap nut 12 so that said nut may be adjusted by rotation of said reflector.

To provide for holding the valve against chance displacement after adjustment thereof, and at the same time to provide means 75 whereby said valve may be shifted or adjusted from one position to another, a collar, as 24, is fixed upon the reduced end 10^a of the plug 10, and a flexible arm 25 extends laterally from said collar. Said arm serves 80 as a lever which may be grasped with the fingers to effect rotation of the valve. A knob 26, or equivalent device, is carried on the outer end of said arm and normally occupies seated position with respect to one of 85 a plurality of seats or sockets 27 provided at suitable points in the face of the reflector 23, whereby the adjusted position of said valve is yieldingly maintained.

What is claimed is—

1. A miner's lamp comprising a water reservoir, two independent gas generating tanks carried on the under side of said reservoir and embodying removable carbide containers, a valve body disposed between said tanks and exterior both to said tanks and to said reservoir, said body having a socket therein, a port leading from said reservoir to said socket, a valve plug in said socket and having an end projecting to a point forward of 90 said reservoir, said plug having a longitudinal gas passage therethrough, a pair of oppositely disposed water tubes leading from the socket in said valve body to the interiors of said tanks, a pair of oppositely disposed 95 gas conducting tubes extending from the socket in said body to the interiors of said tanks, said valve plug having a pair of recesses therein, one of which is adapted to afford an avenue of communication between 100 said port and one of said water tubes and the other of which provides communication 105 between one of said gas tubes and the passage in said plug, said plug being rotatable to simultaneously remove said recesses from 110 register with the last mentioned tubes and to present them in register with the opposite tubes.

2. A miner's lamp comprising a water reservoir, two independent gas generating 115 tanks carried on the under side of said reservoir and embodying removable carbide containers, a valve body disposed between said tanks and exterior both to said tanks and to said reservoir, said body having a socket 120 therein, water conducting means leading from said reservoir to said socket, a valve plug in said socket and having a gas passage extending longitudinally therethrough, the outer end of said plug having a burner 125 130

tip, opposite alined water ports in said valve body, water conducting tubes leading from said ports to the interiors of said tanks, opposite alined gas ports in said valve body, 5 and gas conducting tubes leading to said gas ports from said tanks, said valve plug being rotatable and being recessed so that in one position it affords communication between said water conducting means and one of said 10 water tubes and between one of said gas tubes and said gas passage, and in another position affords communication between said water conducting means and the other of said water tubes and between the other of 15 said gas tubes and said gas passage.

3. A miner's lamp comprising a water reservoir, two independent gas generating tanks carried on the under side of said reservoir and embodying removable carbid containers, a valve body disposed between said tanks and having a socket therein, water conducting means leading from said reservoir to said socket, a valve plug in said socket and having a gas passage extending 20 longitudinally therethrough, the outer end of said plug being provided with a burner tip, adjustable means retaining said plug in said socket, a reflector carried by said retaining means, said reflector having a plurality of seats in its face, means carried by 25 said plug and engageable with said seats whereby the former may be secured in adjusted position, opposite alined water ports in said valve body, water conducting tubes leading from said ports to said tanks, opposite alined gas ports in said valve body, and gas conducting tubes leading to said gas 30 ports from said tanks, said valve plug being adapted to be alternately rotated to positions affording communication between said water 35 conducting means and said water ports and at the same time affording communication between said gas ports and said gas passage.

ports and at the same time affording communication between said gas ports and said gas passage. 40

4. A miner's lamp comprising a water reservoir, two independent gas generating tanks carried on the under side of said reservoir and embodying removable carbid containers, a valve body disposed between said tanks and having a socket therein, water conducting means leading from said reservoir to said socket, a valve plug in said socket and having a gas passage extending longitudinally therethrough, the outer end 45 of said plug being provided with a burner tip, adjustable means retaining said plug in said socket, a reflector carried by said retaining means, said reflector having a plurality of seats in its face, means carried by 50 said plug and engageable with said seats whereby the former may be secured in adjusted position, opposite alined water ports in said valve body, water conducting tubes leading from said ports to said tanks, opposite alined gas ports in said valve body, and gas conducting tubes leading to said gas 55 ports from said tanks, said valve plug being adapted to be alternately rotated to positions affording communication between said water 60 conducting means and said water ports and at the same time affording communication between said gas ports and said gas passage. 65

In testimony whereof, I affix my signature in presence of two subscribing witnesses. 70
